GAS CARTRIDGE FIRING DEVICE

Scott M. Abbott, Chicago, Ill.

Application September 28, 1932, Serial No. 635,214

8 Claims. (Cl. 42—2)

This invention relates to improvements in gas cartridge firing devices and it consists of the matters hereinafter described and more particularly pointed out in the appended claims.

5 The primary object of the invention is to provide a small compact device for firing a chemical cartridge to produce a discharge of tear or like gas.

A further object of the invention is to provide 10 a device of this kind which though shorter in overall length than other devices, now on the market for the same purpose, is capable of employing a gas cartridge of greater volume.

Another object of the invention is to provide 15 a device of this kind including a casing and a barrel partway withdrawable from and retractable into the casing, the latter so holding the cartridge that the barrel in its retracting movement operates to fire the same, the gas being discharged out through the barrel.

The above mentioned objects of the invention, as well as others, together with the many advantages thereof, will more fully appear as I proceed with my specification.

25 In the drawing:

Fig. 1 is a perspective view of a gas cartridge firing device embodying the preferred form of my invention, shown in its cocked position.

Fig. 2 is a longitudinal sectional view through 30 the same showing the parts in said cocked position.

Fig. 3 is a view similar to Fig. 2 showing the parts in the position they occupy when the device has been fired.

35 Fig. 4 is a transverse sectional view through the same as taken on the line 4—4 of Fig. 2.

Fig. 5 is a perspective view of the barrel of the device.

Fig. 6 is a perspective view of a certain annular 40 ring embodied in the improved device for providing a seat or shoulder for the cartridge.

Fig. 7 is a perspective view of a removable breech-block embodied in my improved device.

In general, the improved device includes a 45 tubular casing closed at one end by a removable breech-block and associated with the other end of the casing is a spring pressed barrel which may be partway withdrawn therefrom into cocked position and held in said position by a trigger. The 50 first mentioned end of the casing is so formed as to receive the fulminating cap end of the cartridge with said cap arranged closely adjacent a firing pin on the breech-block.

The inner end of said barrel is formed to receive the other end of the cartridge with a sliding

fit and is provided with an internal shoulder. When the trigger is actuated to release the barrel and the same is retracted into the casing by its associated spring, said shoulder engages said other end of the cartridge and forcefully moves the same against the firing pin to discharge the cartridge. Means are provided whereby the trigger may be held at "safety" when the barrel is in cocked position so that the device may be carried in the pocket or supported in this condition 10 from a hook or the like by means of a ring connected to the breech-block.

Referring now in detail to that embodiment of the invention, illustrated in the accompanying drawing:

15 1 indicates as a whole the tubular casing or holder of the device, which is internally threaded at one end and is provided at its other end with an inturned radial flange 2 that defines an opening 3 in said last mentioned end of the casing 20 or holder. On the outside of the flange 2 is a semicircular annular flange 4 and on the inside thereof is a complete annular flange 4a.

25 Threaded into the first mentioned end of the casing is a ring 5 best shown in perspective in Fig. 6 and this ring is provided in its outer end with an annular seat 5a to receive the closed and flanged end 6 of a gas cartridge 7. This cartridge is of the kind having the conventional center fulminating cap (not shown). Removably threaded into said last mentioned end of the casing is a breech-block 8 that closes said end of the casing. In the inside of said block is a recess 9 of a diameter to receive the flange of the cartridge and centrally in said block is mounted a 30 fixed firing pin 10. The outer side of said block is provided with a boss 11 in which is operatively engaged a ring 12 by means of which the device as a whole may be suspended from a suitable supporting hook or the like.

35 40 45 50 55 13 indicates as a whole (see Fig. 5) the barrel of the device having an external diameter approximating that of the casing opening 3 whereby said barrel may slide therethrough. On that end of said barrel normally within the casing is a radial flange 14. The other end of said barrel that is normally outside the casing is threaded to receive a flanged ring 15 and midway between its ends, said barrel is provided in its exterior with an annular groove defining a radial shoulder 16 that extends completely around said barrel.

The inner or flanged end of the barrel has an internal diameter for a part of its length that snugly receives the discharge end of the cartridge as best shown in Figs. 2 and 3 whereby said end

of the cartridge is guidingly supported. The outer end of said barrel has an internal diameter slightly less than that of the first mentioned end, thus providing an annular shoulder 17 on the inside 5 of the barrel.

Surrounding the barrel and extending between the flange 14 thereof and the flange 2 of the casing is a helical expansion spring 18 which normally acts to urge the barrel into its retracted position 10 toward the breech-block end of the casing.

19 indicates a trigger that normally acts to hold the barrel in its partly withdrawn, cocked position but which may be manipulated to release the barrel whereby the spring 18 retracts the barrel 15 into firing position. Said trigger includes a stem 20 having the desired flexibility and one end thereof is made to provide a hook 21 that may be inserted into an opening 22 provided in one side 20 of the casing. The other end of said trigger is made 25 as a ring 23 that projects over the flanged end 2 of the casing and surrounds the barrel as well as the semicircular flange 4 thereon.

The trigger 19 is made of spring stock which 25 normally urges the stem away from the casing and thus holds that side of the ring 23 opposite the stem in close engagement with the barrel. By reason of said ring surrounding the semicircular flange 4, said ring is held against a laterally shifting movement.

30 Slidable on the stem of the trigger is a safety catch 24 that has an inside extension 25 at that end associated with the flanged end of the casing. When the catch is slid down the trigger stem, toward its hooked end 21, then the extension so 35 engages the side of the casing as to prevent the trigger from being pressed inwardly. When the safety catch has been moved upwardly of the stem, toward the ring 23 this brings the extension beyond the flanged end of the casing (as best 40 shown in dotted lines in Fig. 2) so that said stem can be pressed inwardly toward the casing and thus release the barrel.

To load the device, the breech-block 8 is unscrewed from the associated end of the casing 1. 45 A cartridge 7 may then be inserted into the casing with its flanged end 6 positioned against the seat 5a in the cartridge seating ring 5. The breech-block is next replaced and this spaces the fulminating cap of the cartridge closely adjacent 50 the firing pin 10 in the breech-block.

To cock the device, the breech-block end is held in one hand and the other hand is then employed to grasp the ring 15 on the barrel. The operator then exerts a relative pulling movement 55 between the casing and barrel and this withdraws the barrel partway out of the casing and places the spring 18 under compression.

In this movement of the barrel out of the casing, so soon as the shoulder 16 passes the ring 23 60 of the trigger, said ring snaps into position behind said shoulder and holds the barrel in its cocked position. In so cocking the device, the flange 14 on the barrel will engage the hooked end 21 of the trigger stem 20 inside of the casing and 65 thus limit the withdrawal movement of the barrel. To lock the barrel in its cocked position the safety catch is slid down the trigger stem so that the extension 25 engages the barrel and prevents inward movement of the stem.

70 With the device in a cocked position, to fire the same, it is held in one hand with the thumb engaged with the safety catch. By a movement of the thumb, the catch is slid upon the stem so as to bring its extension beyond the end of the 75 casing when a slight inward thumb pressure is

imposed upon the catch. This will remove the ring 23 from under the shoulder 16, when the spring 18 will forcefully urge or retract the barrel into the casing.

When the internal shoulder 17 of the barrel 5 engages the discharge end of the cartridge, it acts to move the cartridge toward the breech-block. In this movement of the cartridge, its fulminating cap is engaged with the firing pin. The cartridge is thus fired and discharges its 10 contents as a gas out through the barrel.

After one operation, the empty cartridges is withdrawn and replaced by a loaded one and the device is ready for the next operation. In this 15 respect, it is pointed out that it may be safely carried loaded in the pocket in either its cocked or uncocked condition.

By reason of using a sliding or movable barrel as described, a longer cartridge having a greater gas capacity may be employed in a device 20 having shorter overall length than has heretofore been possible.

The device comprises but a few parts which are simple to make and easy to assemble and thus 25 the device can be made and sold at a relatively low cost and it is easy to operate and is safe in its operation.

While in describing the invention, I have referred in detail to the form, arrangement and construction of the various parts thereof, the 30 same is to be considered merely as illustrative so that I do not wish to be limited thereto, except as may be specifically set forth in the appended claims.

I claim as my invention:

1. In a device of the kind described, a casing, a barrel partway withdrawable from and retractable into one end of said casing, means providing an external annular shoulder on said barrel positioned beyond said end of said casing when said barrel is so partway withdrawn therefrom, means movable transversely of said end of the casing for releasably engaging said shoulder, and means associated with fixed parts of said casing and barrel and operating when said barrel is thus 40 released to cause a forceful retraction thereof into said casing.

2. In a device of the kind described, a casing, a barrel partway withdrawable from and retractable into one end of said casing, means providing an external annular shoulder on said barrel positioned beyond said end of said casing when said barrel is so partway withdrawn therefrom, means carried by the casing and including a part associated with said end of the casing and surrounding said barrel and adapted to engage said shoulder to releasably hold the barrel in said partway withdrawn position, and means associated with fixed parts of said casing and barrel respectively and operating upon release of said 50 barrel to forcefully retract the barrel into said casing.

3. In a device of the kind described, a casing, a barrel partway withdrawable from and retractable into one end of the casing, means providing an external annular shoulder on said barrel positioned beyond said end of said casing when said barrel is so partway withdrawn therefrom, means carried by the casing and including a part associated with said end of the casing and surrounding said barrel and adapted to engage said shoulder to releasably hold the barrel in said partway withdrawn position, means associated with fixed parts of said casing and barrel respectively and operating upon release of said barrel to force- 70 75 80 85 90 95

fully retract the barrel into said casing, and means for locking said releasing means against operation.

4. A device of the kind described embodying 5 therein a tubular casing, means removably engaged in one end of said casing and coacting therewith in holding a cartridge, a barrel partway withdrawable from and retractable into the other end of said casing, means on one end of 10 said barrel and normally arranged without said end of the casing for grasping and withdrawing the same, spring means in said casing and so engaging said barrel as to act in normally retracting the same into the casing and means on the 15 outside of the casing and operating to engage a fixed part of the barrel when so partway withdrawn as to hold said barrel in said partway withdrawn position, said means being manipulatable to release the barrel to permit its retraction into the casing and so engage the cartridge 20 as to fire the same.

5. A single shot gas cartridge firing device embodying therein a tubular casing, a barrel telescopically mounted therein, a firing element 25 mounted in one end of the casing, means normally acting to cause a forceful retraction of the barrel into the casing, releasable means for holding the barrel in its projected position, means fixed with respect to said end of the casing for holding one end of a cartridge, the other end of 30 which extends into the barrel when the same is in its projected position, and means on the inside of the barrel for engaging the last mentioned end of the cartridge when said holding 35 means is released for causing a movement of said cartridge so that its flanged end engages said firing element.

6. A single shot gas cartridge firing device embodying therein a tubular casing, a barrel tele- 40 scopically mounted in one end of the casing, a breech-block removably engaged in the other end of the casing, a firing element carried by said breech-block, means normally acting to cause a forceful retraction of the barrel toward said other 45 end of the casing, releasable means for holding the barrel in its projected position, means im- movably secured in said breech-block end of the casing for guidingly holding the flanged end of a cartridge, the other end of which extends into the barrel when the same is in its projected position and means on the inside of the barrel for 50 engaging the last mentioned end of the cartridge

when said holding means is released for causing a movement of said cartridge so that its flanged end engages said firing element.

7. A single shot gas cartridge firing device embodying therein, a casing, a barrel partway withdrawable from and retractable into one end of the casing, releasable means associated with said end of the casing for holding the barrel in its partway withdrawn position with respect to 10 said end of the casing, a fixed annular member adjacent the other end of said casing for holding the flanged end of a cartridge, after the same has been inserted therethrough in the loading of the device, the other end of the cartridge then 15 engaging in said barrel when the same is in its partway withdrawn position, an internal shoulder in said barrel spaced from the associated end of the cartridge when the barrel is in its partway withdrawn position, a firing element in said other end of the casing beyond said annular member, 20 and means operating upon release of said holding means for retracting the barrel into the casing so that said internal shoulder engages the associated end of the cartridge to forcefully move the flanged end thereof in guided engagement 25 with said annular member, against the firing element.

8. A single shot gas cartridge firing device embodying therein, a casing, a barrel partway withdrawable from and retractable into one end of the casing, releasable means associated with said 30 end of the casing for holding the barrel in its partway withdrawn position with respect to said end of the casing, a breech-block removably engaged in the other end of the casing, a firing element carried by said block, a fixed annular member forwardly of the breech-block for holding the flanged end of a cartridge after the cartridge has been inserted therethrough in the loading of the device, the other end of the cartridge then 35 engaging in said barrel when the same is in its partway withdrawn position, an internal shoulder in said barrel spaced from the associated end of the cartridge when said barrel is in its partway withdrawn position, and means operating 40 upon the release of said holding means for retracting the barrel into the casing so that said shoulder engages its associated end of the cartridge to forcefully move the flanged end thereof in guided engagement with said annular member 45 against said firing element.

SCOTT M. ABBOTT.
